UNITED STATES PATENT OFFICE.

JOHN A. HULIT, OF CHICAGO, ILLINOIS.

RECORDING TELEGRAPH MACHINE.

Original application filed March 22, 1917, Serial No 156,556. Divided and this application filed May 22, 1919, Serial No. 298,939. Renewed November 12, 1921. Serial No. 514,826.

To all whom it may concern:

Be it known that I, JOHN A. HULIT, a citizen of the United States, residing at Chicago, in the county of Cook and State of Illinois, have invented a certain new and useful Improvement in Recording Telegraph Machines, of which the following is a specification.

This invention relates to recording telegraph machines and more particularly to means for connecting up the pen. Among the objects of my invention are the following:

To provide an improved means for connecting the pen with the controlling electromagnet.

To provide means whereby the pen may be removed from the device and for indicating the position to which the pen must be returned to preserve the original adjusted position.

To provide means in a device of the above character in which there is one particular position for the pen, and means whereby the pen may be removed quickly from that one position to the same position, and to provide details of improvement tending to increase the efficiency and serviceability of a device of the above character. To accomplish the foregoing useful ends my invention makes use of means hereinafter more fully set forth and claimed.

This application is a division of my prior application, Serial No. 156,556, filed March 22, 1917.

Figure 1 is a front elevation of a recording telegraph machine embodying the principles of the invention, showing certain portions removed for convenience of illustration, this view corresponding to Figure 7 of said prior application.

Figure 2 is an enlarged detail sectional view of the clamping device by which the fountain pen is secured to the rock shaft upon which is also mounted the armature of the magnet, this view corresponding to Figure 9 of said prior application.

Figure 3 is a vertical section in Figure 1 on line 3-3, on a smaller scale, being similar to Figure 4 of said prior application, except that in this case, of course, the other form of fountain pen is shown.

In the particular embodiment of the invention shown in the drawing a suitable base 10 is provided adapted to be attached

by screws 12, to the frame 13 or some other suitable part of the recording device, equipped with a bed or table 14 carrying the record sheet or strip of paper or the like 16, propelled by suitable mechanism. 60 Pivotedly mounted on the base 10 is a vertical post or pillar 18 detachably secured in suitable position by any suitable means, such as a set screw 20 in the base 10. This post or pillar 18 perforates a flat horizontal 65 plate 22 which is itself detachably secured to the pillar 18 by any suitable means, such as a set screw 24. It will be seen that by a proper manipulation of the set screws 20 and 24 suitable adjustment of the parts 10 70 and 22 may be effected with reference to each other. The plate 22 supports the coils of an electromagnet 28 and carries on its underside a bar 30 of insulating material upon which the magnet terminals 32 are 75 mounted, electrical connection between these terminals and the coils being made by suitable wires. Rising from the front plate 22 is a post 36 having extending from it an arm 38 through which is screw-threaded the 80 lower contact point on a contact screw 40 adjustably secured in position by a lock nut in the ordinary manner. Pivotedly mounted in a horizontal plane across the top post 36 is another arm 44 similar in size 85 and dimensions to the arm 38. This arm 44 is pivoted on and detachably secured to the post 36 by the screw 46, so that the operator can by tightening or loosening the last mentioned screw, lock the arm 44 in position with the screw 48 in juxtaposition to the screw 40, or swing the arm 44 to the position shown in Fig. 3. The set screw 50 it will be seen is screw threaded through the arm 44 in the ordinary manner. When the 90 arms 38 and 44 are in normal position, that is, when the screw point 48, Fig. 3, is swung over to its position behind the post 36, with the point 48 directly above and opposite the point 40, they normally have between them 95 and control the length of the stroke of the armature 52 of the magnet 28. But when the arm 44 is swung to the left as shown in Fig. 3, the upper contact 48 is out of the way of the armature, so that the armature 100 can be raised to a position as shown in Fig. 3. The armature 52 is rigidly secured by any suitable means to the shaft 104. The rear end of the armature 52 is attached to one end of the spring 70, the other 110

2

end of which is attached to the shaft to any suitable support. Detachably connected to the post 18 is provided the arm 100 and held in place by suitable set screw 68. This arm 100 has an upturned end 102 serving as a bearing for the one end of the shaft 104, the other end of which shaft is suitably pivoted in the post 18. At the outer end of the shaft 102 is a rectangular enlargement or block 106 held in place by a pin 108, the outer end 108^a of which serves the purpose of a positioning pin for the flat metallic clip 110 which is held in position by the set screw 112. This screw passes through a suitable opening in the clip 110. The outer end of the clip is curved to embrace and securely hold the fountain pen 116. The point 118 is adapted to bear upon the tape 16. The positioning pin 108 and the holes in the clip as well as the hole for the set screw 112 are accurately made and positioned so that by removing the screw 110 the pen 116 and the clip 110 may be lifted as a unit from enlargement with the controlling device and yet restore quickly and accurately to its own original position of adjustment, in which position the pen can function in the way that it should in connection with the tape 16. It will be understood that the armature 52 is detachably and adjustably secured to the shaft 104 by a set screw 84. It will be understood that spring 70 serves to hold the armature 52 in its normal raised position against the contact point 48, and when the contact is removed out of the way it operates to rotate the shaft 104, thereby raising the armature 52 to the position shown in Fig. 3, and likewise the pen 116 to the correspondingly raised position from which position the pen and clip may be conveniently removed without any danger of marking up or interfering with the tape 16.

From the foregoing it will be seen that the marking device (which is the fountain pen 116) and the armature 52 (the latter being composed of an arm which is adjustable on the rock shaft 104 and which supports the armature proper 152 directly above the magnet spools 28, it being understood that the entire magnet comprises two of these spools arranged side by side) oscillate in unison about a horizontal axis common thereto, the armature arm 52 and the fountain pen 116 working up and down in parallel vertical planes which are spaced apart a distance for convenience of operation of the machine as a whole. The magnet pulls the armature down, against the adjustable screw 40, and when the magnet is de-energized, the spring 70 pulls the armature arm 52 upward against the screw 48, and this is the normal position of the armature, so that the fountain pen is normally raised a distance above the surface of the tape. With this arrangement, and by the provision of the screw 84 by which the armature is secured to the shaft 104 (without this screw the armature is loose on the shaft) the armature and marking device are relatively adjustable about the said axis, so that by loosening the screw 84, while the armature is held in engagement with the screw 48, the point of the pen or marking device may be raised and lowered to obtain the desired adjustment, and by then tightening the screw 84 the pen or marking device will be held in its adjusted position relatively to the armature. It will be understood, of course, that this adjustment is obtained by rocking or oscillating the shaft 104 in the arm of the armature, so that the armature is in one sense relatively adjusted on the shaft, while loose thereon and then secured thereto by the tightening of said screw. Thus the upturned end portion 102 of the bracket 101 forms one bearing for the rock shaft, while the upper end of the post 18 forms the other bearing for said rock shaft, and it will be seen that the bearing 102 is disposed between the armature and the fountain pen or marking device, whereby the latter is disposed in an overhanging position and in a position in which it can be easily adjusted or taken out and replaced. The fountain pen, of course, is susceptible of endwise adjustment in the spring clip or holder 110, as the latter holds the barrel of the pen by frictional grip or pressure thereon, so that this adjustment is possible if necessary or desirable. With this arrangement, therefore, the horizontal axis which is common to the pen and armature is disposed between the upper and lower ends of the pen or marking device, so that the pen or marking device is easily tilted or vibrated or operated in the desired manner. It is not necessary for the pull of the magnet to raise the entire weight of the pen, nor is it necessary for the spring 70 to raise the entire weight of the pen or marking device, as the weight of the latter is very well balanced at opposite sides of said axis of oscillation or tilting movement. Thus, the upper end of the fountain pen assists the spring 70 in raising the pen point from the tape, which would not be the case if the weight of the fountain pen or marking device was disposed entirely at one side of the axis of movement, and in such case the spring would be under the necessity of lifting the entire weight of the marking device. This tends to make the instrument more satisfactory, in some ways, of course, inasmuch as the work of the magnet and the spring are reduced to the requirement of merely tilting or oscillating a rock shaft about the axis of which the marking device is fairly well balanced, so that the weight of the marking device does not interfere

with the rapid and accurate operation of the machine by the electrical impulses transmitted through the coils of the magnet.

What I claim as my invention is:

5 1. In a recording telegraph device, a pen, an electromagnet, an armature for the magnet for controlling said pen, a clip attached to said pen, a pair of pins for holding the clip in position while in connection with the 10 armature, and means for locking the clip in such position.

2. In a recording telegraph device, a pen, an electromagnet, an armature for the magnet for controlling said pen, a clip attached 15 to said pen, a pair of pins for holding the clip in position while in connection with the armature, means for locking the clip in such position, said means comprising a shoulder on one of said pins.

20 3. In a recording telegraph device, a pen, an electromagnet, an armature for the magnet for controlling said pen, a clip attached to said pen, a pair of pins for holding the clip in position while in connection with the 25 armature, means for locking the clip in such position, said means comprising a shoulder on one of said pins, one of said pins provided with threads for locking the shoulder in position.

30 4. In a recording telegraph device, a pen, an electromagnet, an armature for the magnet and a support operated by the armature for controlling said pen, a clip attached to said pen, the clip having a pair of holes and 35 the support having a pin and a thread hole so that when one of the holes on the clamp is over the pin the other one of the holes falls in juxtaposition to the threaded hole on the support, and a threaded screw with a 40 shoulder for said threaded hole to retain the clip in position.

45 5. In a recording telegraph device, a clip having a curved forward end for holding a fountain pen and provided near its center with a hole adapted to receive a thumb screw, said clip being also provided at its rear end with a centering hole for a centering clip of a printing machine.

50 6. In a printing telegraph instrument, the combination of an electromagnet, a vibratory armature therefor, a recording device, means whereby said armature and said device are supported independently of each other to oscillate in unison about an axis common thereto, said recording device being a marking device disposed transversely of said axis, and with the axis located between the opposite ends of said device, so that one end tends to counterbalance the other, means whereby said armature and said device are relatively adjustable about said axis, and means to

limit the vibratory motion of the armature.

7. A structure as specified in claim 6, having a spring to actuate said armature and said device in one direction, adapted to yield 65 to permit attraction of the armature by the magnet, the projecting rear end of said marking device serving by its weight to assist said spring in raising the other end of said device when said magnet is de-energized.

8. A structure as specified in claim 6, said axis being formed by a rock shaft having said armature and said device spaced apart a distance thereon, and a support forming a 75 bearing for said axis at a point between said armature and said device.

9. In a printing telegraph instrument, the combination of a vibratory recording device, electromagnetic operating means, said device 80 and means being supported independently of each other, a spring cooperating with said electromagnetic means to vibrate said device about an axis at right angles to the plane of vibration thereof, means whereby said recording device is adjustable endwise at an angle to said axis, and a tape traveling under the marking end of said device.

10. In a printing telegraph instrument, the combination of a rock shaft, a fountain pen 90 on said shaft, an armature on said shaft, means whereby said fountain pen is readily removable from the outer end of said shaft, so that the pen can be removed and replaced and adjusted without disturbing the shaft, 95 said pen and said armature being spaced apart to vibrate in parallel planes, and an electromagnet to operate said armature.

11. A structure as specified in claim 10, said pen and said armature being disposed 100 at the same side of said shaft, so that both move down in unison, and a tape traveling under said pen, together with means whereby the rear end of said fountain pen projects a distance at the other side of said 105 shaft to counterbalance the marking end thereof, said magnet being disposed under said armature.

12. In a printing telegraph instrument, a fountain pen and an armature supported independently of each other and arranged to vibrate in parallel planes about an axis common to both of them, at the same side of said axis, means whereby the entire fountain pen is removable and replaceable without disturbing said armature, a tape traveling at 110 right angles to said axis, and an electromagnet to operate said armature.

Signed by me at Chicago, Cook County, State of Illinois, this 13th day of May, 1919. 120

JOHN A. HULIT.
